Primary Examiner — Lauren D McVey(74) *Attorney, Agent, or Firm* — Kilpatrick Townsend & Stockton LLP(57) **CLAIM**

The ornamental design for command pod module, as shown and described.

DESCRIPTION

FIG. 1 is a front perspective view of command pod module showing our new design;

FIG. 2 is a right side front perspective view thereof;

FIG. 3 is a left side front perspective view thereof;

FIG. 4 is a rear perspective view thereof;

FIG. 5 is a front elevational view thereof;

FIG. 6 is a right side elevational view thereof;

FIG. 7 is a rear elevational view thereof;

FIG. 8 is a left side elevational view thereof;

FIG. 9 is a top view thereof; and,

FIG. 10 is a bottom view thereof.

The broken lines immediately adjacent the shaded areas represent the bounds of the claimed design while all other broken lines are directed to environment and are for illustrative purposes only; the broken lines form no part of the claimed design.

1 Claim, 10 Drawing Sheets(56)
